UNITED STATES PATENT OFFICE.

LUKASZ KRAWIEC, OF PITTSBURGH, PENNSYLVANIA.

PACKAGE-HANDLING DEVICE.

1,280,618.

Specification of Letters Patent.

Patented Oct. 1, 1918.

Application filed September 8, 1917, Serial No. 190,362. Renewed September 5, 1918. Serial No. 252,790.

To all whom it may concern:

Be it known that I, LUKASZ KRAWIEC, a subject of the Emperor of Austria, residing at Pittsburgh, in the county of Allegheny and State of Pennsylvania, have invented 5 certain new and useful Improvements in Package-Handling Devices, of which the following is a specification.

This invention relates to package handling 10 devices and has special reference to a device for use in loading and unloading freight and baggage cars, the device being constructed for the purpose of handling with ease the packages such as trunks, boxes, 15 bales, and the like both in loading the cars and in unloading the same.

One important object of the invention is to improve and simplify the general construction of devices of this character.

20 A second important object of the invention is to provide a device of this character which is of novel construction and is so arranged that a minimum of labor is required in handling packages even though they may 25 be very heavy and clumsy.

A third important object of the invention is to provide an improved device of this character which includes a traveling package carrier arranged to run along from one 30 end to the other of a train platform, the device also including car supported package receiving elements so arranged that they may lower the desired packages from the traveler to the car floor in the process of 35 loading and in the process of unloading lift the packages from the car floor level onto the traveling carrier.

A fourth important object of the invention is to provide an improved device of 40 this description wherein what may be termed the elevating devices are so arranged that they may lift certain selected packages off of the carrier while at the same time the carrier is permitted, after the packages have 45 been lifted off, to travel on to the next elevating device.

With the above and other objects in view, as will be hereinafter apparent the invention consists in general of certain novel details 50 of construction and combinations of parts hereinafter fully described, illustrated in the accompanying drawing, and specifically claimed.

In the accompanying drawing, like characters of reference indicate like parts in the several views, and in which:

Figure 1 shows a side elevation of a car with the parts in position for unloading.

Fig. 2 is a cross section through a car showing the device positioned therein. 60

Fig. 3 is a plan view of the inside of a car with the device located therein and showing the driving engine.

Fig. 4 is a side view of the device as it appears in the car. 65

Fig. 5 is a transverse section through the railroad tracks showing the movable carrier.

Fig. 6 is a section through a part of the car showing the engine and its connection 70 to the device.

Fig. 7 is an enlarged detail showing one end of the crane runway.

Fig. 8 is a section on the line 8-8 of Fig. 7 to show the driving of the crane. 75

In general the invention consists of a traveling carrier arranged in fixed relation to a crane truss or bridge, the latter moving over an elevated crane runway of the ordinary type from one side of a train 80 platform and tracks to the other side thereof. In connection with this traveling carrier the supporting part of which consists of certain fingers there are positioned within the car certain elevating devices so arranged that when a train is on a track alongside of the platform these devices will come beneath the crane runway. These elevating devices also have their supporting surfaces consisting of fingers and the fingers of the 85 elevating device pass between the fingers of the carrier in the upward and downward movement of the elevating device so that after the carrier is positioned over an elevating device upward movement of the latter will lift any packages desired upward 90 off of the carrier. 95

In the present embodiment of the invention the general arrangement is shown in Fig. 5 wherein there is disclosed a platform 100 having at one side thereof railroad tracks 10 having at one side thereof railroad tracks 11 whereon run cars indicated at 12. Supported on suitable columns 13 is a runway 14 having the usual rails 15 for the wheels 16 of a crane truss or bridge 17. Connected 105 to the beams of this crane truss or bridge are brackets 18 and to these brackets are secured the upper and inner ends of finger bars 19 the lower ends of which are curved outwardly as at 20 to extend laterally toward the sides of the crane runway, the extremities of these finger bars being indi- 110

cated at 21. These finger bars are held in position by suitable braces 22 and are connected in spaced relation by an I-boss 23. Moreover, the curved portions 20 of the 5 finger bars are held apart by braces 24. It is to be noted that the portions 21 of the finger bars lie slightly above the level of the car top.

This crane with its attachments constitutes the traveling carrier on which the packages are placed for distribution to the various cars and this carrier is caused to traverse the crane runway by means of suitable gearing connected to one of the wheels 15 16 and which is here shown at 23, one of the gears being carried on the shaft 26. This shaft 26 is revolved by any desired means as for instance the motor 27 and gear 28 but it is to be observed that I do 20 not confine myself to a motor and gear for actuating the shaft but may employ any form of motor such as is ordinarily used to cause a crane to run along its runway.

Within each of the cars 12 is located an 25 elevating device and each of the elevating devices, in the form best shown in Figs. 2, 3, and 4 inclusive, is provided at its four corners with screw threaded posts 29 which are mounted in supports 30 at the top and 30 bottom. On these posts 29 slides a frame 31 and this frame is supported on the respective posts by means of nuts 32, each post carrying a sprocket wheel 33 all of the sprocket wheels being connected together to revolve 35 in unison by a chain 34. One post 29 is provided with a gear 35 wherewith meshes a gear 36 carried on a shaft 37 capable of being revolved by gearing 38 so that the operator by revolving the gearing 38 causes revolution of all of the posts 29 and thus raises 40 or lowers the frame 31.

Supported above the frame 31 by suitable braces 40 are finger bars 41 these finger bars being of such dimensions and so arranged 45 that when the traveling carrier stops centrally over an elevating device the finger bars 41 will lie below and between the finger bars 21 so that operation of the gearing 38 will raise the finger bars 41 upward between the finger bars 21 and thus lift off the latter any package which may be resting thereon. The movement is reversed after 50 the car has moved away from beneath the crane runway so that the finger bars 41 may 55 attain the lowest position within the car.

At one side of each of the car carried devices is a conveyer belt 42 one of the pulleys of which is located on the shaft 37 and adjacent this conveyer belt is a loading incline 60 or chute 43. In order to operate the gearing 38 one of the gears is supported on a shaft 44 which is connected by suitable sprockets and a chain 45 with an engine indicated in general at 46 the engine being of any desired 65 type and it being obvious that an electric

motor may replace the engine. Furthermore, in order to permit the passage of the carrying frames upward through the car a suitable hatchway 47 is provided having supported thereabove a sliding door 48 70 which may be closed when desired to protect the car from the weather. From the foregoing it will be seen that packages may be placed on one-half of a car supported frame and the crane supported frame placed 75 in such position, with other packages thereon, that the car may be run past the station without stopping. Thus the upwardly curved portions of the finger bars will effect transferal of packages on the finger bars 80 from one frame to the other.

There has thus been provided a simple and efficient device of the kind described and for the purpose specified.

It is obvious that many minor changes 85 may be made in the form and construction of the invention without departing from the material principles thereof. It is not therefore desired to confine the invention to the exact form herein shown and described but 90 it is wished to include all such as properly come within the scope claimed.

Having thus described the invention, what is claimed as new, is:—

1. The combination with an overhead 95 traveling crane; of a package carrier supported by said crane, and car supported elevating devices positioned below the path of travel of said carrier and movable vertically to lift packages off of said carrier. 100

2. The combination with an overhead traveling crane; of a package carrier supported by said crane and including a plurality of spaced laterally extending fingers, a car supported elevating device positioned below the path of travel of said fingers and including a plurality of spaced laterally extending fingers arranged to lie intermediate the fingers of the carrier, and means to move the fingers of the elevating device vertically 110 through the spaces between the fingers of the carrier.

3. The combination with an overhead traveling crane; of a package carrier supported by said crane and including a plurality of spaced laterally extending fingers, a car supported elevating device positioned below the path of travel of said fingers and including a plurality of spaced laterally extending fingers arranged to lie intermediate 120 the fingers of the carrier, said elevating device also including a supporting frame, nuts carried by the supporting frame, screw posts passing through said nuts, and means on the frame to rotate all of the posts simultaneously. 115

4. The combination with an overhead traveling crane; of a package carrier supported by said crane and including a plurality of spaced laterally extending fingers, a 130

car supported device positioned below the path of travel of said fingers and including a plurality of spaced laterally extending fingers arranged to lie intermediate the fingers of the carrier, said elevating device also including a supporting frame, nuts carried by the supporting frame, screw posts passing through said nuts, sprockets on said posts, a sprocket chain connecting all of said 10 sprockets, operating means, and gearing connecting the operating means and one of said posts.

5. The combination with a train platform having tracks at the side thereof and a crane 15 runway extending thereacross, of a traveling crane on said runway, a package carrier

supported by the crane and having package supporting fingers extending laterally in a plane above the top of a car on one of said tracks, and a car supported elevating device 20 including fingers normally below the first-mentioned fingers and arranged to pass vertically therebetween, said elevating device being arranged to lift packages off the carrier and transfer them to the plane of the 25 car floor.

In testimony whereof I affix my signature.

LUKASZ KRAWIEC.
